FIG-1-

INVENTOR=
BURT H. MACY
by *Burt H. Macy*
ATTORNEYS

UNITED STATES PATENT OFFICE.

BURT H. MACY, OF SOMERVILLE, MASSACHUSETTS.

ELEVATOR-LOCKING SYSTEM.

1,270,854.

Specification of Letters Patent.

Patented July 2, 1918.

Application filed May 18, 1915. Serial No. 28,938.

To all whom it may concern:

Be it known that I, BURT H. MACY, a citizen of the United States, and resident of Somerville, in the county of Middlesex and State of Massachusetts, have invented certain new and useful Improvements in Elevator-Locking Systems, of which the following is a specification.

The object of the present invention is to provide an automatic means adapted for use with elevators in apartment houses and elsewhere which are not operated by a regular operator always stationed in the car, but by any one who has occasion to come into the building, for the purpose of making impossible the operation of the elevator car when any door is open. The invention particularly relates to elevators which are controlled by the mechanical action of a shipper rope, which sets the hoisting mechanism in operation. My object is to lock the shipper rope by a single pair of jaws and to control said jaws by all of the doors opening into the well, and further to accomplish this object by an improved and simple mechanism. A further object is to furnish an improved and simplified construction of elevator lock adapted for use generally with elevators of which the controller is a rope, by which I mean any element capable of being arranged and operated in essentially the same manner as the common shipper rope of an elevator. In the drawings,

Figure 1 is an elevation somewhat diagrammatic of a lock embodying my invention installed in an elevator well, in connection with means by which the doors to the well control the lock.

Fig. 2 is a plan view of the improved lock in which my invention is embodied, said figure representing the casing of the lock as being cut away.

Fig. 3 is a section on line 3—3 of Fig. 2 showing the lock in longitudinal section and in closed position.

Fig. 4 is a view similar to Fig. 3 showing the jaws of the lock in open position.

I will first describe the mechanical construction of the lock and then explain the mode in which it is arranged and operated. The lock is contained in a casing 5 having a passage at one end adapted to admit a shipper rope 6, such passage being surrounded by lips 7 with flaring interior sur-

faces, of a common design. Jaws 8 and 9 55 are mounted in the casing and project partly across the passage therethrough, being located at opposite sides of the center of the passage. The jaw 8 is somewhat hook-shaped and is carried by a shank 10 which 60 slides in the casing adjacent to one side thereof. The jaw 9 is connected to a shank 11 disposed in the opposite side of the casing. A tailpiece or arm 12 projects from the shank 11 across the casing into the line 65 of movement of the shank 10 and a spring 13 is confined between the end of said shank 10 and the end of said tailpiece. A lever 14 is pivoted on a stud 15 in the casing between the shanks 10 and 11, and has two arms with 70 rounded ends contained in recesses 17 and 18 of the shanks 10 and 11. On the outer side of the end of the casing are formed two bosses 19, 19 which are centrally bored and in which are slidingly contained rods or 75 plungers 20, 20, the inner ends of which bear against the transverse tailpiece 12. An extension frame 21 forms a part of the casing 5 and supports a pivot rod 22 on which are mounted a series of levers 23. These levers are all alike and each has an arm 24 extending from the pivot rod approximately perpendicular to the line of action of the plungers 20 and the shanks of the jaws. The arms 25 of said levers extend approximately 80 horizontally and are engaged with springs 26. There is one spring to each lever, as appears clearly from Fig. 2. These springs are also fastened to the bottom plate 27 of the frame 21.

A presser bar 28 is hung by ears 29 from a pivot rod 30, which is mounted in the frame. This bar bears on the ends of the two plungers 20 and lies contiguous to the shorter arms 24 of the levers 23. The springs 26 tend to hold the levers 23 in the position shown in Fig. 3, in which position they cause the latter to press upon the bar 28 and transmit pressure through the plungers 20 to the shank 11, holding the jaw 9 in the closed position and 100 acting through the lever 15 to hold the jaw 8 also in the closed position. In this position the jaws enter the space between two knobs or buttons 31, 32 or other abutments on the shipper cable, leaving an open space less 105 wide than the buttons and making it impossible to shift the cable.

The spring 13 tends to open the jaws, that

is, to retract them from the shipper rope, but this spring is less powerful than any one of the springs 26 so that it is overcome when any spring 26 is free to actuate its respective lever 23.

Referring to Fig. 1, I have shown diagrammatically an elevator well with the doors 33 opening into the well from different floors of the building, and I have also shown the shipper cable, although I have not illustrated the elevator car. The lock is shown at 5 with one of the stretches of the shipper rope passing through the channel in which the locking jaws enter. In this figure, 15 34 represents cords, wires, chains or other flexible connecting means which lead from the several doors to the several levers 23. The length of each cord is such that it is tightened when the door to which it is connected is closed, and is shifted to such an extent as to lift the lever arm to which it is connected against the tension of the spring 26 far enough, as shown in Fig. 4, to enable 20 spring 13 to open the jaws. When a door is opened, the line 34 connected thereto is relaxed and the spring 26 is permitted to depress the lever which is connected to that cord and thereby to close the jaws.

It will be appreciated that when all of 30 the doors are closed, all of the lever arms 25 are raised and the locking jaws are opened to release the shipper cable, making it possible to operate the elevator car. But whenever any one of the doors is opened, 35 the cord 34 connected to that door is slackened and the lever 23 connected thereto is caused to close the jaws.

My invention resides principally in the improved means by which each one of a 40 number of doors is adapted to operate the same lock, such means comprising the levers 23, each of which is connected to one of the doors and is able to actuate the jaws. In this mechanism the presser bar 28 is an important element in connection with the two widely separated presser plungers 20, as it transmits the pressure of any one of the levers 23 to the plungers in a straight line and without side thrust. The plungers move 50 freely and with equal facility when operated by any one of the levers regardless of the location of the lever.

The invention is not restricted, however, to this means or mechanism, since it also resides in the other features of the lock apart from the feature of a plurality of operating members, and particularly in the idea of a combination of jaws with external means for applying force to one of them, to move it, 60 and internal means for imparting an equal and opposite movement to the other. It will be noted that the lever or rocker 14 is not in itself a means for opening or closing the jaws, but is rather a transmission member 65 which transmits motion from one jaw

to the other; the proximate operating means being either or both of the plungers 20 acting on the tailpiece 12 of the jaw 9. In the construction of the transmission rocker lies another feature of the invention, of great 70 practical importance in that the rounded ends of such rocker, occupying concave recesses in the shanks of the jaws constitute an association having great simplicity, the minimum of parts, and adapted to be assembled without fitting or finishing the contacting surfaces, and consequently at low cost.

What I claim and desire to secure by Letters Patent is:

1. An elevator controlling mechanism comprising in combination with a shipper cable, a lock including locking jaws adapted to prevent operation of said cable when closed and to permit such operation when open, a plurality of levers mounted in association with said lock and each operable independently of the others, a plurality of doors opening into the elevator well, and motion-transmitting elements each in permanent connection with one of said levers and with one of said doors, each door being connected by said elements with a separate one of said levers.

2. An elevator lock comprising a casing 95 having a passage for a shipper rope, sliding jaws on each side of said passage, a plunger adapted to bear against a portion of one of said jaws, a presser bar bearing against said plunger and a plurality of levers arranged 100 side by side, each arranged to bear against said bar and transmit motion thereto.

3. A shipper cable lock comprising a locking element, a plunger arranged to apply pressure against said element to close the same, a plurality of levers arranged side by side and a pressure transmitting medium interposed between said levers and bearing against said plunger arranged to transmit pressure from any one of said levers to the 110 plunger.

4. A shipper cable lock comprising a locking element, a plunger arranged to apply pressure against said element to close the same, a plurality of levers arranged side by side and a pressure transmitting medium interposed between said levers and bearing against said plunger arranged to transmit pressure from any one of said levers to the 115 plunger, said pressure transmitting medium being of rigid construction and supported independently of the plunger.

5. An elevator lock and operating mechanism comprising a series of duplicate levers independently mounted side by side, operating means for each lever, a bar of rigid construction pivoted to swing on an axis parallel to that of the levers and arranged to be engaged by each of said levers, a movable locking device, and transmission means in- 120 125 130

terposed between said bar and said device for moving the latter in consequence of movement of the bar.

6. A shipper cable lock comprising a casing having a passage for a cable, complementary jaws on each side of said passage connected and operable to move in unison toward and away from the center of the passage, a plurality of operating levers mounted side by side on said casing and each operable independently of the others, and transmitting means between said levers and one of said jaws arranged for transmitting the movement of any one of said levers to the jaws.

7. A lock for the shipper cable of an elevator comprising a locking element adapted to prevent movement of such cable when in one position and to permit movement thereof when in another position, a plurality of operating members mounted side by side and each capable of independent operation, and motion transmitting means between said levers and said locking element, arranged for actuation by any one of said operating members for shifting said locking element from one of its positions to the other.

8. A lock for the operating rope of an elevator comprising coöperating jaws, a spring arranged to react between said jaws

tending to hold the latter in open position, a lever having arms engaged with the jaws respectively whereby to transmit movement from one to the other, and external means arranged to act upon one of the jaws for moving the same into the closed position against the resistance of said spring.

9. An elevator lock comprising independently mounted movable slides each having a jaw and being guided and arranged to travel in substantially parallel paths, one of said slides having a tailpiece, a spring interposed between said tailpiece and the other slide arranged and operative to hold the slides and jaws in a predetermined position, external actuating means arranged and operable to act against one of said slides to displace it from the position in which it is held by said spring, and transmission means engaged with both slides for causing the other slide to be moved simultaneously with and oppositely to the slide which is moved by the actuating means.

In testimony whereof I have affixed my signature, in presence of two witnesses.
